UNITED STATES PATENT OFFICE.

JAMES E. KENNEDY, OF WASHINGTON, DISTRICT OF COLUMBIA.

WATER-HEATING GRID.

Application filed April 29, 1922. Serial No. 557,257.

To all whom it may concern:

Be it known that I, JAMES E. KENNEDY, a citizen of the United States of America, residing at Washington, in the District of Columbia, have invented certain new and useful Improvements in Water-Heating Grids, of which the following is a specification.

This invention relates to water heating grids for gas stoves and ranges, and the general object of the invention is to provide means for utilizing the waste heat from gas burners for heating water so that the same will prove of general benefit for household use so as to provide hot water in stand boilers commonly employed with cooking ranges.

The primary object of the invention is to provide a simple, inexpensive and practical form of grid for gas stoves whereby water may be efficiently heated whenever desired and particularly while the burner is being employed for the cooking of food, thereby resulting in economy by avoiding the necessity of a separate heater for obtaining hot water.

With these general objects in view and others that will appear as the nature of the invention is better understood, the same consists in the novel construction combination and arrangement of parts hereinafter more fully described, illustrated in the accompanying drawings, and pointed out in the appended claims.

In the drawings:

Figure 1 is an elevational view of a grid constructed in accordance with the present invention.

Figure 2 is a top plan view of the device shown in Figure 1.

Figure 3 is a substantially central transverse sectional view of the device shown in Figure 2.

Figure 4 is a horizontal sectional view taken on line IV—IV of Figure 1, and

Figure 5 is a fragmentary substantially radial sectional view on line V—V of Figure 2.

Referring more in detail to the several views, the invention embodies certain modifications of the usual form of grid which is adapted to be removably supported upon a suitable ledge of a stove frame above the burner 5 of the stove, which grid embodies

a plate portion 6 that is supported in a horizontal position when in use and which has a central opening for the upward passage of the flames and the heat of the burner to the cooking vessel, a tubular depending flange or sleeve 7 being formed integral with and projecting perpendicularly from the under surface of the plate portion 6 and being preferably disposed between the inner and outer peripheries of the plate as clearly shown in Figure 2. The usual form of grid embodies radial inwardly extending and uniformly spaced fins 8 adapted to more effectively radiate the heat from the burner and the present invention contemplates forming these fins of tubular construction with tubular connections 9 and 10 alternately provided for the fins respectively at the outer and inner ends thereof so that a continuous passage is provided of a tortuous nature for the circulation of water therethrough. The tubular connections 9 and 10 may be readily provided in a casting operation with the inner wall of each of the connections 10 co-operating with the adjacent portion of the sleeve 7.

The sleeve 7 is preferably of a greater length than the connections 9 and 10 and fins 8 so as to extend slightly below the latter and surround the burner 5 for confining the heat from the latter and insuring upward passage of all of such heat through the central opening of the grid. The projecting portion of the sleeve 7 is provided with notches or cut out as at 11 and 12 (see Figures 1 and 3,) for reception, respectively of the inlet or feed pipe 13 and supporting lug 14 of the burner which is preferably of the construction specifically set forth in my co-pending application for gas stoves, Serial No. 551,283, filed Oct. 29, 1921. In order to obtain maximum benefit of the heat from the burner the latter is preferably constructed as set forth in my above mentioned application so that the flames therefrom will diverge upwardly and strike the side walls of the fins 8 the latter being provided with beveled lower edges as indicated at 15 in Figure 3 so as to properly deflect the flames.

For economy in manufacture, one of the outer connections 10 is formed but rendered inoperative by vertically tapping the same and then inserting a screw plug cen-

trally thereof as at 16 to form a partition between the inlet and outlet fins of the grid. The inlet fin communicates with a relatively long hollow enlargement 17 which is cast 5 integral with the sleeve 7 externally of the latter and which is provided with an inlet opening at its lower end adapted in any suitable way for connection with the water supply pipe 18, and a similar but shorter 10 hollow lug 19 is cast on the sleeve 17 in communication with the outlet fin. The lug 19 is disposed with its outlet port at a higher elevation than that of the lug 17 so that a proper circulation will be had by reason 15 of the cold water entering on a lower level than the level at which the hot water flows out of the outlet fin. An outlet pipe 20 is connected to the lug 19 in any desired manner but the connection for the pipes 18 and 20 is preferably a threaded one as illustrated in Figure 5.

In operation, the grid is placed operatively above the burner 5 in the usual manner and the lugs 17 and 19 respectively connected with water supply and delivery pipes 18 and 20 as found most convenient, whereupon when the burner is lighted, the heat of the burner may be utilized for cooking purposes and will simultaneously instantaneously heat 30 the water flowing through the serially connected heat radiating fins 8 for providing hot water.

From the foregoing description it will be seen that I have provided a commercially 35 practical form of grid having a construction and appearance greatly similar to the characteristics of ordinary grids and which will lend itself to existing manufacturing methods with slight modifications.

40 While the form of the invention herein shown and described is what is believed to be the preferred embodiment thereof, it is nevertheless to be understood that various forms, modifications and arrangements of 45 the parts may be made without departing from the spirit and scope of the invention as claimed.

What is claimed as new is:—

1. A water heating grid for gas stoves and 50 the like embodying a grid plate with a central opening and inwardly projecting heat radiating fins extending inwardly of said opening, tubular connections provided alternately between the inner and outer ends of 55 the fins forming a continuous circulatory tortuous passage for water, means providing a partition between two adjacent fins, and means to respectively connect said two fins internally with water supply and delivery 60 pipes.

2. A water heating grid for gas stoves and 65 the like embodying a grid plate with a central opening and inwardly projecting heat radiating fins extending inwardly of said opening, tubular connections provided alter-

nately between the inner and outer ends of the fins forming a continuous circulatory tortuous passage for water, means providing a partition between two adjacent fins, and means to respectively connect said two fins internally with water supply and delivery pipes, said last named means involving external hollow lugs upon the grid with ports disposed at different elevations whereby the cold water enters at a lower level than the 75 level of the outlet of the hot water.

3. A water heating grid for gas stoves and the like embodying a grid plate with a central opening and inwardly projecting heat radiating fins extending inwardly of said opening, tubular connections provided alternately between the inner and outer ends of the fins forming a continuous circulatory tortuous passage for water, means providing a partition between two adjacent fins, and means to respectively connect said two fins internally with water supply and delivery pipes, said partition providing means constituting a removable screw plug threaded into the grid to obstruct the passage of 90 water through one of the tubular connections for the outer ends of the fins.

4. A water heating grid for gas stoves and the like embodying a grid plate with a central opening and inwardly projecting heat radiating fins extending inwardly of said opening, tubular connections provided alternately between the inner and outer ends of the fins forming a continuous circulatory tortuous passage for water, means providing a partition between two adjacent fins, and means to respectively connect said two fins internally with water supply and delivery pipes, said grid further embodying a depending sleeve, portions of 100 which constitute the outer walls of the tubular connections between the outer ends of the fins.

5. As an article of manufacture, a water heating grid for gas stoves or the like embodying a grid plate having inwardly projecting hollow heat radiating fins serially connected alternately by hollow members at the inner and outer ends thereof for providing a continuous tortuous circulatory conduit for water, means to supply and deliver water to and from adjacent ones of a pair of such fins respectively, and means to prevent passage of the water from one of said two fins to the other.

6. A water heating grid for gas stoves embodying a grid plate with hollow inwardly projecting heat radiating fins internally serially connected alternately at the outer and inner ends thereof to provide a tortuous conduit for water, adjacent two of such fins having means to respectively connect the same to water supply and delivery pipes at opposite sides of the adjacent outer connecting means therefor.

7. A water heating grid for gas stoves embodying a grid plate with hollow inwardly projecting heat radiating fins internally serially connected alternately at the outer and inner ends thereof to provide a tortuous conduit for water, adjacent two of such fins having means to respectively connect the same to water supply and delivery pipes, said fins having upwardly diverging lower edges for deflection of upwardly diverging 10 flames directed thereagainst.
- 5 In testimony whereof I affix my signature.

JAMES E. KENNEDY.
